(57) **CLAIM**

The ornamental design for a merchandising display unit for bottles, as shown and described.

DESCRIPTION

FIG. 1 is a perspective view of our new design;

FIG. 2 is a top plan view of the new design;

FIG. 3 is a front elevational view of the new design;

FIG. 4 is a rear elevational view of the new design; and, FIG. 5 is a left side elevational view of the new design, the right side being a mirror image thereof.

The bottom of the display unit for bottles forms no part of the claimed design.

The surface(s) or portion(s) of the article not shown in the drawing or described in the specification form(s) no part of the claimed design.
